UNITED STATES PATENT OFFICE

WILLIAM S. PETTY, OF DENVER, COLORADO, ASSIGNOR, BY DIRECT AND MESNE ASSIGNMENTS, TO KAY-PETTY MFG. CO.

IRONING TABLE

Application filed June 27, 1927. Serial No. 201,655.

My invention relates to ironing tables, and is a companion to my ironing table invention, Patent No. 1,723,439, August 6, 1929.

Therefore the object of this invention is to provide an apron which may either be manufactured at the factory as an integral part of the ironing table, or which may be attached thereto after its manufacture, and which will in either case hold the portions of the goods not being ironed and keep them off the floor and away from the feet of the operator.

In the drawings:—

Figure 1 is a view looking down on my ironing table, the position of the apron when swung to the position under the smaller board being indicated by dotted lines.

Figure 2 is a side elevation of my table as shown in Figure 1.

Figure 3 is a section taken on the line 3—3 of Figure 1.

Figure 4 is a perspective of a portion of the apron frame.

Figure 5 is a portion of my table showing a modified mounting for the apron frame.

Figure 6 is a perspective of a portion of the apron frame shown in Figure 5.

Figure 7 shows a portion of my table with another modified mounting for the apron frame.

Figure 8 is a perspective of a portion of the apron frame shown in Figure 7.

Figure 9 shows a portion of my board with another modified mounting for the apron frame.

The main board 1 or main ironing surface of the ironing board is hinged to the base 2 so that it may be raised out of the way as indicated by the dotted lines in Figure 2. This is for convenience when the floor is to be cleaned.

The sleeve board 3 or secondary ironing surface, is preferably pivoted to the base 2 by a pivot pin such as shown at 4.

In the form shown in Figures 1, 2, 3, and 4, the pin 4 is extended at its lower end to receive the bracket 7, which is held on the pin 4 by the washer 5 and the pin 6.

The bracket 7 is provided with apertures to receive the apron frame side members or

rods 8 and 9, which are securely fastened in the bracket 7 by the set screws 10.

The apron 11 preferably made of muslin or canvas or other cloth is provided with two loops which are adapted to slip over the apron frame rods 8 and 9. When the apron 11 becomes soiled it may be easily replaced with a clean apron by slipping the soiled apron from the frame rods 8 and 9 and slipping the clean apron on the rods in its place. An apron of metal or other suitable material may be used if desired, though I prefer muslin, canvas or other cloth as stated above.

The details of construction of the pivot pin 4 and of the apron bracket 7 may be varied as desired so long as the final result is a pivotally mounted apron bracket that will permit the intended pivotal movement.

The bracket 7 and the rods 8 and 9 when assembled constitute a U-shaped frame or frame work, that is, a three sided, open ended frame.

In operation, the article being ironed is placed in the apron and the portions of it desired are pulled up and placed upon the board.

When the sleeves or other parts requiring a smaller board are to be ironed the apron frame is swung about its pivot till the apron is under the small board 3, as indicated by the dotted lines in Figure 1. It may be swung into this position also, when the main board 1 is raised out of the way on its hinges as indicated by the dotted lines in Figure 2.

In any case, the apron is swung under either board to the position where it may be most conveniently used, the goods are kept clean, are kept up off the floor and the feet of the operator are in no way obstructed at any time or in any position of the apron.

In the modified form shown in Figure 5 the bracket 7 is of symmetrical form as shown in Figure 6, since the mounting pivot pin 4' in this form is in the center of the base 2, being supported by the lugs 15 which are integral with the base 2. In this form the two apron frame rods 14 may be straight.

The bracket, rods and pivot pin 4' may of course be made in any of the forms mentioned

in regard to the construction shown in Figure 1, or in any other proper manner.

In the modified form shown in Figure 7 the pin 4' is mounted in a lug 17 integral with the base 2, the rods 16 being similar but of right hand and left hand shape and formed as shown in order to permit the use of as long an apron as possible, and allow the swinging movement on the pivot 4', when the small board 3 is used without interference of the rods 16 with the base 2.

The pin 4', may be screwed, riveted, clamped, welded or in any other proper manner mounted on the base 2 instead of being pressed into the lug 17 as long as it acts to provide a suitable support for the bracket 7. The apron frame may be made as shown in Figure 8 or in any other proper manner as indicated above for the other forms of apron frames.

20. In the modified form shown in Figure 9 the pin 4' is mounted in a bracket 18, which is screwed to the main board 1 by the screws 19.

25. In this construction an apron frame similar to that shown in Figure 8 may be used.

30. The bracket 18 and pin 4' may be made in one piece if desired, and instead of the screws shown it may be attached to the board 1 by bolts or rivets; or the pin 4' may be made in the form of a large screw and screwed into the board 1, or into a metallic insert made in the board 1. In any case the result will be the same in that the pivot 4' will be mounted on the board 1, and will be raised with it, when the board 1 is swung up out of the way about its hinge, as indicated by the dotted lines in Figure 2. Thus in this form the entire apron construction may be swung up out of the way with the board 1.

40. It will be noted that in the other forms shown the entire apron construction is swung under the small board 3 when the main board 1 is raised to make room for cleaning the floor.

45. In any form, of course, if desired, the entire apron construction may be removed by dismounting the bracket 7 from its pin.

50. I am aware that there are various other methods of mounting my apron construction upon the ironing board, which modifications any experienced mechanic would readily perceive after my invention had been disclosed to him.

55. I am also aware that there are various other forms of cantilever ironing tables, with different base constructions, and different connections between the base and the boards, and upon which my apron frame either stationary or pivoted could be mounted with only the slight changes that might be needed to meet the new constructions.

60. So, I do not wish to limit myself narrowly to the exact forms and constructions shown, but what I claim as new, and desire to protect by Letters Patent, is as follows:—

1. In an ironing table a main board supported adjacent one end only and provided with a pivotal mounting pin located below the main board and adjacent its supported end, an auxiliary board pivotally mounted upon said pin, and a frame having an attached fabric forming therewith a receptacle pivotally mounted upon said pin. 70

2. In an ironing table a main board supported adjacent one end only and provided with a pivotal mounting pin located below the main board and adjacent its supported end, an auxiliary board pivotally mounted upon said pin, and a frame having an attached fabric forming therewith a receptacle pivotally mounted upon said pin whereby the auxiliary board and the receptacle may swing concentrically away from the main board, and the receptacle may be swung under the main board and away from the auxiliary board. 75

3. In an ironing table, a main board supported adjacent one end only and provided with a pivotal mounting pin located off-center below the main board and adjacent its supported end, an auxiliary board pivotally mounted upon said pin, and a frame having a fabric and forming therewith a receptacle pivotally mounted on said pin. 80

4. In an ironing table, a main board supported adjacent one end only and provided with a pivotal mounting pin located off-center below the main board and adjacent its supported end, an auxiliary board pivotally mounted upon said pin, and a frame having a fabric and forming therewith a receptacle pivotally mounted on said pin, whereby the auxiliary board and the receptacle may swing concentrically away from the main board, and the receptacle may be swung under the main board and away from the auxiliary board. 100

In testimony whereof I affix my signature.
WILLIAM S. PETTY.
